Primary Examiner — Antoine Duval Davis(74) *Attorney, Agent, or Firm* — Jose Cherson Weissbrot(57) **CLAIM**

The ornamental design for a wire locator tracker lan, as shown and described.

DESCRIPTION

FIG. 1 is a first perspective view of a wire locator tracker lan showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the wire locator tracker lan in which the design is embodied that form no part of the claimed design.

1 Claim, 8 Drawing Sheets(56)
